UNITED STATES PATENT OFFICE

2,098,528

FOUNTAIN PEN VALVE

Anatol N. Andrews, Los Angeles, Calif.

Application May 23, 1936, Serial No. 81,453

1 Claim. (Cl. 120—48)

My invention relates to a fountain pen, and more particularly to a non-leaking fountain pen, and is a fountain pen valve which does not require the ink container for a member in its construction. Its principal objects are:

First.—To prevent the leaking of the ink from the ink container when the cap is screwed into place over the point.

Second.—To make its application possible in fountain pens which do not use the rubber sac as a direct ink container.

Third.—To make its application possible in fountain pens which do not use a rubber sac.

Fourth.—To make a shut off member in a fountain pen independent from the ink container.

Fifth.—To be simple, efficient and durable.

Sixth.—To be susceptible of economical manufacture.

In attaining my objects, I change the general structure of the current fountain pen very little, the principal difference being that in my improved pen, provision is made in the middle portion of the feed channel for valve and band seats. Then a band made of soft, flexible, springy and resilient material is stretched and mounted in the band seat and over the valve seat.

A press button, preferably spherical, is mounted over the band and the valve seat, and is movably held in a valve opening in the pen barrel, for instance, by the walls thereof. The band and the walls of the feed channel seal the press button and the valve opening from the ink in the ink container, feed channel and valve seat, thus making the valve independent from the ink container and also applicable in fountain pens which have no rubber sac adjacent to the feed channel.

When the cap is not in place over the point the outer portion of the press button extends beyond the outer wall of the barrel,—and in the sliding movement into the place over the point the walls of the cap force the button into the valve seat against the band,—a portion of the band under the pressure stretches and fills the valve seat thus preventing the ink from the container and the upper portion of the feed channel to pass through into the lower portion of the feed channel.

When the pressure against the button and the band is removed, the latter resumes its original position, mounted over the valve seat, from thus restoring free passage for ink from the container to the lower portion of the feed channel via channel's upper portion and the valve seat.

The features of this invention for which the protection of Letters Patent of the United States is desired, are collectively grouped in the claim concluding this specification.

In the drawing, which illustrates one specific

form of my invention, the figure is a transverse section of a fountain pen equipped with my improvement.

Referring to the drawing, the figure shows a fountain pen of one particular type, this being composed of the head 4, feed element 5, barrel 1, valve press button (ball) 10, valve barrel opening 11, feed channel 6, 7 and 8 (7 and 6 being the lower portion, and 8—the upper portion thereof), valve band and the band seat 3A, and valve seat 9.

In equipping this pen with my improvement the valve seat 9 is made in the shouldered upper portion of the head 4 and the feed channel 6, 7 and 8, and divides the latter into the lower portion 7 and 6, and the upper portion 8,—and the band 3A is made of soft, flexible, resilient and springy material capable to stretch, and is stretched and mounted in the band seat over the valve seat 9. The valve press button may consist of a ball 10, which in the normal writing condition of the pen structure is positioned as indicated on Fig. 3, where the resiliency of the material of the band 3A tends to push the ball 10 outwardly through a frusto-conical opening 11 formed in the barrel 1,—and the opening 11 is of smaller diameter than ball 10 thus preventing the latter to fall out.

As shown on the figure, the opening 11 and ball 10 are sealed from the ink container, valve seat 9 and channel 6, 7 and 8, by the band 3A and walls of the feed channel 6, 7 and 8.

While specific embodiments of this invention are herein shown and described, it is to be clearly understood that variations within the scope of the accompanying claim, may be resorted to without jeopardizing my patent protection.

Having fully described my invention, what I claim is:

In a fountain pen a sacless shut off valve which is independent, separated and sealed from pen ink container, and includes in combination a tubular band of soft, flexible, stretching and springy material mounted over the middle section of feed channel walls and a valve seat, and the band is not extended into the ink container, and is not a part thereof,—and a valve seat mounted in the feed channel and separated from the ink container by the upper section of the feed channel and walls thereof,—and a press button mounted in an opening in the lower section of the pen over the tubular band and the valve seat,—and the opening and the press button are insulated and sealed from the ink and the ink container by the tubular band and walls of the feed channel.
